UNITED STATES PATENT OFFICE.

HEINRICH JACOB, OF STEGLITZ, AND JULES HUMBRECHT, OF GROSS-LICHTERFELDE,
NEAR BERLIN, GERMANY, ASSIGNORS TO THE FIRM OF OPTISCHE ANSTALT C. P.
GOERZ AKTIENGESELLSCHAFT, OF FRIEDENAU, NEAR BERLIN, GERMANY.

PERISCOPE.

1,098,905.

Specification of Letters Patent.

Patented June 2, 1914.

Application filed July 26, 1910. Serial No. 573,961.

To all whom it may concern:

Be it known that we, HEINRICH JACOB and JULES HUMBRECHT, citizens of the German Empire, and residents of Steglitz, near Berlin, and Gross-Lichterfelde, near Berlin, respectively, Germany, have invented certain new and useful Improvements in and Relating to Periscopes, of which the following is a specification.

The present invention relates to periscopes for submarine vessels and its object is to facilitate the mounting and working of the instrument. To this end the rotatory reflector of the instrument, which enables the observer to take a panoramic view without changing his position, is mounted in a light tube rotatable in a massive casing or mantle (to which the ocular may be fixed), with a transparent extension which surrounds the reflector and preferably forms a cap on the casing. The transparent part or cap of the casing may have various shapes; for instance, it may have the shape of a cylinder, or of a segment of a sphere.

When using a transparent cylinder for inclosing the rotatory reflector, it is necessary to neutralize the distortion of the image caused by the cylinder. For this purpose, there may be arranged inside the transparent cylinder fixed to the casing, a cylinder-lens connected with the reflector, and disposed at an angle of 90° to the transparent cylinder. The reflector may also be coupled with a positive cylinder-lens without angular displacement of the cylinder axes.

The reflector is usually formed by a reflecting surface of a prism, and in this case the prism surface in front of the reflecting surface entrance may be so ground that the distortive effect of the transparent cylinder is neutralized. When the rotatory reflector is mounted in a transparent hollow sphere, the distortive effect on the image may be taken into account in computing the optical system of the telescope.

The invention is illustrated in the annexed drawings, as applied to a panorama periscope.

Figure 1 is a longitudinal section of the entire instrument, Fig. 2 a longitudinal cross section of the ocular end of the instrument, taken in a plane at 90° to the plane of Fig. 1, Figs. 3 and 4 are longitudinal sections illustrating two forms of construc-

tion of the head piece of the periscope. 55 Fig. 5 is a fragmentary detail sectional view showing, on a larger scale than in Fig. 1, the mechanism for actuating the image erecting prism on rotation of the entrance reflector.

In the instrument shown in Figs. 1 and 2, the rotatory reflector (Fig. 1) is marked 1, and is mounted in a light tube 2. The latter is surrounded by a massive jacket or mantle tube 3 and can be rotated therein by means of bevel gear wheels 4, 5, the wheel 5 being connected to a crank handle 6 outside the tube 3. The ocular 7 is arranged in the massive tube 3.

In the example shown in Fig. 1, the rotatory reflector 1 is inclosed by a transparent cylinder 8 making a liquid-tight joint with the tube 3 and closed at the top by a cap 9, also liquid-tight.

Fig. 3 shows more closely the connection 75 of the transparent cylinder with the mantle tube, and the closure of the upper end of the transparent cylinder by the cap 9. The cap 9 has an overhanging rim 10 serving as an elastic buffer to reduce the force of accidental blows. The cylinder lens 11 placed in front of the reflector 1 and rigidly connected therewith, serves to neutralize distortion of the image by the cylinder 8. The lens 11 is so arranged that its axis is at 80 85 right angles to the axis of the transparent cylinder 8.

In Fig. 4 the transparent mantle surrounding the reflector 1 consists of a segment of a transparent sphere, with a metal 90 cover or cap 13 at the top, having a laterally projecting rim 14 for reducing the effect of lateral blows.

The optical elements of an embodiment of a telescope provided with the new kind of 95 mounting of the rotatable reflector are shown diagrammatically in dotted lines in Fig. 1. In this figure the numerals 15^a and 15^b designate a pair of lenses forming an image producing system; the lenses 16^a 100 and 16^b form an image reverting system; 17^a and 17^b form a lens combination for producing parallel rays and 18^a, 18^b designate an image enlarging lens combination. 19 is an image reverting prism in firm connection with a beveled gear 20 rotatably guided within tube 2. 21 is a beveled gear 105 rotatably mounted in tube 2 and meshing with

gear 20. Mounted on the same stud 22 as gear 21 is a further beveled gear 23 meshing with a toothed beveled circle 24 mounted within the mantle 3 of the instrument. This connection between the fixed outer mantle 3 and the rotatable inner tube 2 causes a rotation of prism 19 within tube 2 on rotation of the latter; the number of teeth of the several gears being so calculated that prism 19 is rotated with half the speed of tube 2 with reflector 1 as it is necessary for obtaining upright images at arbitrary positions of reflector 1 as is well known to those skilled in this special branch of industry.

15. What we claim is:

1. In a periscope a mantle tube having a transparent extension, a reflector firmly mounted therein at the end opposite said transparent extension and adapted to throw rays of light passing through said mantle casing laterally outside the same and a rotatory tube placed within said mantle tube having substantially the same length and carrying an entrance reflector at the end adjacent the transparent extension of the mantle tube and optical means for producing images from distant objects emitting rays striking said entrance reflector and further optical means for compensating for the effect of rotation of the entrance reflector.
2. In a periscope a mantle tube having a transparent extension liquid-tightly connected with said mantle tube and provided with a cap having a laterally projecting rim

distortable by impact and a rotatory tube 35 placed within said mantle tube and carrying a reflector at the end adjacent said transparent extension of the mantle tube.

3. In a periscope a mantle tube having a cylindrical transparent extension, a rotatory tube placed within said mantle tube, a reflector mounted in said rotatory tube at the end adjacent the transparent extension, and a cylinder lens arranged in front of said reflector and in firm connection therewith, 40 said cylinder lens being adapted to compensate for the distortion of the image of distance objects caused by the transparent cylindrical extension of said mantle tube.

4. In a periscope, a mantle tube, a rotatory tube placed therein and carrying an entrance reflector for luminous rays, a transparent cylinder surrounding said entrance reflector, and curved transparent means in front of said entrance reflector so constructed as to form substantially undistorted images from distant objects on said reflector and an immovably mounted exit reflector for said rays.

In testimony whereof we have signed this 60 specification in the presence of two subscribing witnesses.

HEINRICH JACOB.
JULES HUMBRECHT.
